BAG AND SACK

Charles Butterfield, Norwood, and Harold W. Nichols, Cincinnati, Ohio; said Butterfield as-
signor to said Nichols

Application April 9, 1931. Serial No. 528,780

5 Claims. (Cl. 229—68)

Our invention relates to millinery, notion, shopping and other bags and/or sacks, having closing flaps which are so arranged as to provide a handle for carrying the bag.

5 There have been a number of structures proposed, and some of them have gone into use for accomplishing in general the purpose of our invention. It is the object of our invention to improve on these devices, and among other 10 things, to provide for a reinforced bag top and for a locking flap which, when closed, will stay closed, and will not be disrupted by the fingers of the person carrying the bag.

By means of the structure to be described, we 15 place the strain of supporting the bag directly on the reinforcing element, and do not call upon the finger holes in the bag itself for doing any of the work, either in holding the locking tab in place, or sustaining the weight of the contents of the bag. Further, we do not have to distort the locking flap in any way when putting it to use, and our bag is cheap and simple to manufacture.

We accomplish our objects by that certain arrangement and construction of parts to be hereinafter set forth, it being understood that we have shown a preferred embodiment, and that in our claims we will set forth the novelty inherent in the structure described.

30 In the drawing:—

Figure 1 is a fragmentary elevation of the top edge of the bag taken from the opposite side of the bag from which the locking flap projects.

35 Figure 1A is a section taken on the line A—A of Figure 1.

Figure 2 is a section taken on the line b—b of Figure 1.

Figure 3 is a fragmentary elevation showing 40 the same side of the bag as Figure 1, after the closing flap has been folded over, but before the locking flap has been tucked in.

Figure 3A is a section on the line c—c of Figure 3.

45 Figure 4 is a fragmentary elevation taken from the same point of view as Figure 3, but with the locking flap turned up under the reinforcing strip.

Figure 4A is a section on the line d—d of Figure 4.

Figure 5 is a perspective taken from the same point of view as Figures 3 and 4, but with the closing flap and locking flap turned upwardly.

In the illustrated bag, a strip of material is 55 folded on itself and glued at the sides to form a

bag 1. One side of the sheet is made longer than the other, so as to form a closing flap 2. Finger holes of suitable shape are formed at 3 in each of the walls of the bag. Secured by gluing to the top edge of that portion of the bag 60 which does not have a closing flap, is a reinforcing strip 4 of suitable weight. The closing flap 2 is formed with a projection 5 to act as a locking flap; and preferably secured by pasting to the locking flap and the closing flap, is a 65 piece of heavier material 6 which may be scored, if desired, as at 7, to reinforce the locking flap and the portions of the closing flap adjacent thereto, and to bridge the top of the handle opening 3 in the closing flap section of the bag. 70

In operation, to close the bag the flap 2 is bent over so as to overlie the reinforcing piece, as shown in Figure 3, and the locking flap is then turned upwardly so as to extend around the reinforcing piece 4, but not to extend through the hand holes in the bag. To this end, the paste used in applying the reinforcing strip 4 terminates at 4a so that the strip 4 is not secured to the wall of the bag at the unglued intermediate portion. 75

It will be evident that no distortion of the locking flap is necessary, nor any interference with folding, likely resulting in tearing out of the hand holes, in locking the bag after it is closed. The bag is supported by the reinforcing strip 4, and by the reinforcement 6 behind the closing and locking flaps, and the fingers of the user can pass through the holes 3 after the bag is closed and locked, grasping that portion of the reinforcing strip and locking element that lies across the finger holes 3. 80

Having thus described our invention, what we claim as new and desire to secure by Letters Patent, is:—

1. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked. 85

2. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate 105 portion unsecured to the bag behind which the locking flap can be tucked. 110

portion unsecured to the bag behind which the locking flap can be tucked, said reinforcing strip extending from one side to the other of the bag.

3. A bag for the purpose described having a closing flap at one side thereof, and a locking flap projecting from an intermediate portion of the closing flap, hand holes in the sides of the bag registering with the locking flap, a reinforcing strip secured to the top edge of the bag opposite the closing flap and having an intermediate portion unsecured to the bag behind which the locking flap can be tucked, and a reinforcing piece secured to the closing flap and extending across the locking flap.
5. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked, said reinforcing strip extending at least along the edge directly opposite the locking flap.
10. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked, said reinforcing strip extending at least along the edge directly opposite the locking flap.
15. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked, said reinforcing strip extending at least along the edge directly opposite the locking flap.
20. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked, said reinforcing strip extending at least along the edge directly opposite the locking flap.

site the closing flap and having an intermediate portion unsecured to the bag behind which the locking flap can be tucked, said reinforcing strip extending from one side to the other of the bag, and a reinforcing piece secured to the closing flap and extending across the locking flap.

5. A bag for the purpose described having a closing flap at one side thereof, and a locking flap projecting from an intermediate portion of the closing flap, hand holes in the sides of the bag registering with the locking flap, and a reinforcing strip secured to the top edge of the bag opposite the closing flap and having an intermediate portion unsecured to the bag behind which the locking flap can be tucked, said reinforcing strip extending at least along the edge directly opposite the locking flap.
